APPARATUS FOR THICKENING AND WASHING MATERIALS

Filed April 17, 1922

UNITED STATES PATENT OFFICE.

ASHELEIGH S. MOSES, OF NEW YORK, N. Y.

APPARATUS FOR THICKENING AND WASHING MATERIALS.

Application filed April 17, 1922. Serial No. 554,121.

This invention relates to apparatus for thickening and washing materials, such as solid substances suspended in a liquor, the thickening being accomplished by the removal of a part of the liquor from the mixture.

One of the objects of this invention is to provide means for thickening the suspended matter or pulp carried by the liquor, where-
10 by the liquor is passed through a separating medium adapted to hold back the suspended matter, and in which said medium may be maintained in a clean condition unobstructed by accumulation of matter thereupon.

15 Another object of this invention is to provide an apparatus for accomplishing such separation in which the separating medium is kept clean by action of the apparatus.

Another object of this invention is to provide a simple and improved method for thickening pulp or like materials, in which the separation is accomplished by subjecting the liquid to variations in pressure.

Another object of this invention is to provide a method and apparatus for thickening the pulp carried by a liquid by which the thickened pulp may be washed.

Further objects will appear from the detail description taken in connection with the accompanying drawing, in which the figure represents a cross-sectional view of an apparatus adapted for carrying out the purposes of this invention.

In the apparatus shown in the drawing, 35 a supply chamber 1, in which the unthickened material may be accumulated by any desired means, is connected by means of a pipe 2 with a pulp chamber 3 enclosed by a casing 4. The pipe 2 connects to an inlet 40 pipe 5 leading into the chamber 3 and provided with perforations 6 through which the liquid supplied may enter the chamber 3. The chamber 3 is further supplied with an outlet 7 having a valve 8 by means of which 45 the thickened pulp may be drawn off when desired.

Above the pulp chamber 3 is arranged a series of filtrate chambers 9 separated from the chamber 3 by a filter 10. The filter 10 50 may be of any well known construction, such as fabric, or as shown in the drawing, a grating 11 upon which are laid courses of gravel of larger and progressively smaller sizes and finally sand so as to form a filter bed 12. The filter 10 lies between the pulp

chamber 3 and the filtrate chambers 9 so that the liquid in passing from the former to the latter must pass upwardly through the filter.

Each filtrate chamber 9 is closed at the top by an elastic diaphragm 13 secured in place by a ring 14 suitably secured to the casing. The ring 14 supports a spider 15 provided with a bearing 16 for a plunger-rod 17 connected by a pitman 18 with a crank on a shaft 19 driven by a belt 20 or other suitable means. The rod 17 carries at its lower end a stirrup 21 carrying a valve 22 in the diaphragm 13. Rotation of the shaft 19 will thus reciprocate the rod 17 so as to alternately raise and lower the elastic diaphragm 13. The cranks on the shaft 19 which operate the diaphragms in the several chambers 9 may be arranged at various angles as indicated in the drawing, so as to equalize the torque on the shaft throughout each revolution.

Above the diaphragms 13, an open chamber or trough 23 is provided by an upward extension of the casing wall, and this trough is provided with a spill-way 24 adapted to discharge into a conveying trough 25 of any suitable construction.

In operation, the liquid from the supply chamber 1 passes through the pipes 2 and 5 and the perforations 6 into the chamber 3 carrying with it, of course, such suspended matter or pulp as may be contained therein. When the chamber 3 becomes filled, the liquid will pass through the filter 10, leaving the pulp behind in the chamber 3, and the chambers 9 will eventually become filled up. When the chambers 9 are full of the filtrate, the reciprocation of the diaphragms 13 will tend to force some of the filtrate out through the valves 21. These valves are, however, made small enough so that all of the liquid displaced by the movement of the diaphragm cannot pass through the valve during the downward stroke thereof.

The result of this will be a momentary pressure applied to the liquid in the chamber 9, thereby forcing some of this liquid downwardly through the filter 12. This flow being in the reverse direction to that taken during the original filtration will tend to carry out of the filter any suspended matter which may have become lodged therein, returning it to the pulp chamber 3. Thus at each upward stroke of the diaphragm 13, the filtrate in the chamber 9 will be sub- 110

jected to a negative pressure, causing an upward flow of liquid through the filter and during the subsequent downward stroke, a positive pressure will be applied to the filtrate, causing a reversal of flow through the filter. Thus by alternations of pressure applied to the liquid in the chamber 9, an alternation of flow through the filter 10 is produced. At each upward flow, a filtering action takes place and at each downward flow a cleaning action of the filter takes place. It will thus be seen that the filter bed is continually kept in a clean condition and at the same time it is continually active in filtering the liquid passed therethrough and confining the accumulated pulp to the chamber 3. This accumulation of pulp naturally tends to thicken the mixture in the chamber 3.

When the pulp mixture in the chamber 3 has become sufficiently thickened, the supply of liquid from the tank 1 may be cut off by the closing of the valve 26 in the pipe 2. Water or other cleaning fluid may then be admitted from another source (not shown) by opening the valve 27. The action of the apparatus is then continued with the cleansing fluid flowing through the chambers 3 and 9, the discharge of the trough 25 being directed to a new destination, if desired. During this action it is evident that the pulp in the chamber 3 will be thoroughly washed and the washing fluid carried off through the filter and the chambers 9. Upon completion of the washing operation, the valve 8 may be opened and the thickened pulp flushed out through the outlet 7.

It is obvious that various changes may be made in details of construction without departing from the spirit of this invention; it is, therefore, to be understood that this invention is not to be limited to the specific details shown and described.

Having thus described the invention, what is claimed is:

1. In the art of concentrating wet pulp or like material, the process comprising, filtering the liquor from the material by passing the liquor upwardly through the filtering medium, and periodically applying alternately positive and negative pressures to the filtering medium, substantially as and for the purpose set forth.

2. In the art of concentrating wet pulp or like material, the process comprising, filtering the liquor from the material by passing the liquor upwardly through the filtering medium, and periodically applying pressures alternately with and against the flow of the liquor, substantially as and for the purpose set forth.

3. In the art of concentrating wet pulp or like material, the process comprising filtering the liquor from the material while

under static pressure by passing the liquor upwardly through the filtering medium, and periodically subjecting the liquor to a counter pressure, substantially as and for the purpose set forth.

4. In the art of concentrating wet pulp or like material, the process comprising, filtering the liquor from the material while under static pressure by passing the liquor upwardly through the filtering medium, and periodically subjecting the liquor alternately to positive and negative pressures, substantially as and for the purpose set forth.

5. In the art of concentrating wet pulp or like material, the process comprising, filtering the liquor from the material while under static pressure by passing the liquor upwardly through the filtering medium, and periodically subjecting the liquor alternately to pressures with and against the flow of the liquor, substantially as and for the purpose set forth.

6. In the art of concentrating wet pulp or like material, the process, comprising, filtering the liquor from the material by passing the liquor upwardly through the filtering medium, and applying periodically a downward pressure to the liquor in order to dislodge the filtered material downwardly from the filtering medium.

7. In the art of concentrating wet pulp or like material, the process, comprising, filtering the liquor from the material by passing the liquor upwardly through the filtering medium, applying periodically alternate opposite pressures to the liquor, whereby the liquor is forced upwardly through the filtering medium and the filtered material is dislodged downwardly therefrom.

8. In the art of concentrating wet pulp or like material, the process, comprising, filtering the liquor from the material by passing the liquor upwardly through the filtering medium, applying periodically a downward pressure to the liquor in order to dislodge the filtered material downwardly from the filtering medium, and accumulating the filtered material below the filtering medium.

9. In the art of concentrating wet pulp or like material, the process, comprising, filtering the liquor from the material by passing the liquor upwardly through the filtering medium, applying periodically alternate opposite pressures to the liquor, whereby the liquor is forced upwardly through the filtering medium and the filtered material is dislodged downwardly therefrom, and accumulating the filtered material below the filtering medium.

10. In the art of washing pulp or like materials, the process comprising, supplying a washing fluid to the material, filtering the fluid from the material by passing

the liquor upwardly through the filtering medium, and alternately establishing and relieving periodically a counter pressure with respect to the fluid flow, substantially as and for the purpose set forth.

11. In the art of washing pulp or like materials, the process comprising, supplying a washing fluid to the material, filtering the fluid from the material by passing

the liquor upwardly through the filtering medium, and periodically subjecting the fluid alternately to pressures with and against the flow thereof, substantially as and for the purpose set forth.

In testimony whereof I affix my signature this 1 day of April, 1922.

ASHELEIGH S. MOSES.
